Primary Examiner — Paula Greene(74) *Attorney, Agent, or Firm* — Buchanan Ingersoll & Rooney PC(57) **CLAIM**

The ornamental design for an inside door handle for vehicle, as shown and described.

DESCRIPTION

FIG. 1 is a front, top and left side perspective view of an inside door handle for vehicle showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The features shown in broken lines in the drawings depict environmental subject matter only and form no part of the claimed design.
